UNITED STATES PATENT OFFICE.

JOSEPH A. COSTELLO, OF CLEVELAND, OHIO, ASSIGNOR TO THE CLEVELAND BRASS MANUFACTURING COMPANY, OF CLEVELAND, OHIO, A CORPORATION OF OHIO.

FAUCET.

Application filed January 15, 1925. Serial No. 2,468.

To all whom it may concern:

Be it known that I, JOSEPH A. COSTELLO, a citizen of the United States, residing at Cleveland, in the county of Cuyahoga and 5 State of Ohio, have invented a new and useful Faucet, of which the following is a specification.

This invention relates to improvements in faucets and more especially to a faucet 10 which comprises a casing having an interior chamber for receiving alcohol or liquid from a tank or reservoir and has a spout adapted to enter the neck of a bottle or other necked receptacle.

One object of this invention is to successfully utilize a rigid tube, which is uniform 15 in diameter from end to end, as said spout and to position said tube below a downwardly discharging fluid-outlet of the hereinbefore mentioned chamber, and to reinforce the upper portion of the tube externally by 20 a reinforcing jacket integral with the casing, and to form a fluid-tight joint between the top edge of the tube and the casing.

Another object is not only to control communication through said outlet by a valve 25 arranged to move upwardly in opening and having a rotatable stem which extends upwardly above the casing and is provided 30 with a quick-acting external thread and has bearing in a stuffing-box comprising an annular body which surrounds said stem and has a lower end face and is rigid with the casing and provided with an internal thread 35 engaging with said thread on said stem, but to cause a member of the valve to extend opposite said face and to utilize said valve-member in cooperating with said face in limiting the opening movement of the valve.

Another object is not only to rotate the valve-stem by a handle operatively embracing the upper end portion of said stem and forced onto and endwise of said stem into place on said stem, but to provide simple, reliable and highly practical means for preventing forcing of said handle upwardly 45 from said stem when the valve is closed.

Another object is to facilitate the assemblage of the component parts of my improved faucet, and to render the faucet convenient and simple and durable in construction.

With these objects in view, and to attain other objects hereinafter appearing, this invention consists in certain features of con-

struction, and combinations and relative arrangements of parts, hereinafter described in this specification, pointed out in the claims, and illustrated in the accompanying drawings.

In said drawings, Figure 1 is a front elevation, partly in section, of my improved faucet. Fig. 2 is a central vertical section taken along line 2—2 in Fig. 1, looking leftward. Fig. 3 is a horizontal section taken along line 3—3 in Fig. 2, looking upward. Fig. 4 is a section taken vertically through the valve-casing along line 4—4 in Fig. 2, looking rearward, but in Fig. 4 the valve is shown in elevation and in its fully open 60 position. Fig. 5 is a horizontal section taken along line 5—5 in Fig. 1, looking upward. In Figs. 1 and 2 is shown a padlock applied as required for preventing rotation 65 of the valve-stem, when the valve is closed, in the direction required to open the valve. Portions are broken away in the drawings to reduce their size and to more clearly show the construction.

My improved faucet comprises a metal 80 casing 7 having an interior chamber 8 and terminating, at its rear end, in a rearwardly projecting internally threaded tubular member 9 adapted to be screwed onto a pipe or tubular member (not shown) employed in 85 forming the outlet of a liquid-supply tank, or onto any liquid-supplying pipe or tubular member with which the chamber 8 is to be placed in communication. It will be observed, therefore, that said chamber has its 90 fluid-inlet at the rear end portion of the casing 7, and said casing and said chamber are shown as extending upwardly from the member 9.

The chamber 8 (see Figs. 2 and 4) has a 95 downwardly discharging fluid-outlet 10 formed at and centrally of the bottom of the forward end portion of the chamber, and an upwardly facing and beveled annular valve-seat 12 is formed at the upper 100 end of and around said outlet.

An upright spout-forming rigid metal tube 13 (see Fig. 2) is arranged wholly below and substantially in line vertically and in communication with the outlet 10, and the casing 7 has a downwardly projecting integral annular member 14 which is arranged to form a reinforcing jacket for and tightly embraces the upper portion of and supports said tube and has a downwardly 110

5 facing annular internal shoulder 15 arranged to cover the top edge of said tube. Said shoulder is spaced farther from the lower extremity of the jacket 14 than from the valve-seat 12, and said jacket participates in the formation of the outlet 10 at and above said shoulder. The tube 13 extends a suitable distance below the jacket 14 and abuts, at its top edge, against and is substantially in fluid-tight relation to the shoulder 15 so as to prevent leakage of liquid at said edge to the outer circumference of the tube, and said tube is uniform in diameter from end to end. By the hereinbefore described construction it will be observed that the lower portion of the tube 13 is adapted to enter the neck of a bottle or other necked receptacle and that said tube forms a highly practical spout and is inexpensively secured to the casing 7.

10 A valve (see Fig. 2) is arranged to control communication through the outlet 10 and therefore controls the supply of liquid to the tube 13 and comprises a section 16 forming the face of the valve and arranged in fluid-tight relation to the seat 12 and thereby closing communication through said outlet in the closed position of the valve. Said valve is arranged to move upwardly in opening and also comprises a substantially vertical rotatable stem 17 arranged above and centrally in relation to the section 16. The stem 17 extends upwardly above the casing 7 and has a quick-acting external thread 18 and a lower end face 19, and the valve also comprises a metal washer 20 interposed between said face and the section 16, and the members 16 and 20 of the valve are secured removably to said stem by a suitably applied screw 21.

15 The top of the casing 7 (see Figs. 2 and 4) has an aperture 22 extending therethrough over the outlet 10 and having an upwardly flaring upper end portion 23, and said aperture is screw-threaded below said flaring portion and concentric in relation to and larger diametrically than members 16 and 20 of the valve. The casing 7 is provided with a stuffing-box comprising a body 25 which surrounds the valve-stem 17 which has bearing in and extends above said stuffing-box, and said body is externally provided with a downwardly facing annular beveled shoulder 26 seated on and in fluid-tight relation to the surrounding wall of the flaring portion 23 of the aperture 22. The stuffing-box body 25 is screw-threaded externally below the shoulder 26 and screwed, at the aperture 22, into the casing 7 below the flaring portion 23 of said aperture and has a lower end face 27 and projects below said aperture, and said body has an internal thread 28 engaging with the thread 18 on the valve-stem. The washer 20 is large enough in external diameter to extend op-

posite the lower end face 27 of the stuffing-box body 25, and the section 16 of the valve is as large in external diameter as the washer 20 so as to afford adequate support to the washer. The mutually engaging threads 18 and 28 of the valve-stem and stuffing-box body have the pitch required to move the valve endwise from its closed position shown in Fig. 2 into its fully open position shown in Fig. 4 substantially during a half-turn of said stem about its axis, and the washer or member 20 of the valve abuts against the lower end face 27 of the stuffing-box body when the valve is in its fully open position, and obviously said face of said body and said member 20 of the valve cooperate in limiting upward movement of the valve.

20 The casing 7 has a laterally projecting external flange 30 formed on the forward portion of the casing and extending substantially from the front of the casing rearwardly and circumferentially of said portion of the casing and having a hole 31 extending through the forward portion of the flange and adapted to receive the bow of a padlock, as will hereinafter appear. The valve-stem 17 extends above the hereinbefore-mentioned stuffing-box and has its upper end portion 32 oblong in cross-section, as shown in Fig. 5, and a handle 33 conforms to and snugly and operatively embraces said portion of said stem and is seated on an upwardly facing shoulder 34 formed on said stem at the lower extremity of said portion of said stem, as shown in Figs. 2 and 4. The handle 33 extends leftward from the valve-stem, as shown in Fig. 1, or rightward from the stem, as shown in Fig. 4, according as the valve is in its closed position or in its fully open position. The handle 33 is provided, 100 at a suitable distance from the axis of the valve-stem 17, with a downwardly extending arm 35 arranged to move opposite and circumferentially of the outer circumferential edge 36 of the flange 30 during leftward rotation of said stem to the extent required to move the valve from its closed position shown in Figs. 1 and 2 into its fully open position shown in Fig. 4. The arm 35 terminates, 105 at its lower end, in a rigid member 37 projecting in the direction of the axis of the valve-stem and arranged under the flange 30 and rearward of the hole 31 in said flange after the required rotation of said stem to the extent required to move the valve from its fully open position shown in Fig. 4 into its closed position shown in Fig. 2, and obviously said member 37 is removed from under said flange 30 during leftward actuation of the handle 33 from the position shown in Fig. 1 to the position shown in Fig. 4.

110 By the hereinbefore described construction and relative arrangement of parts it will be observed that the arm 35 of the 130

handle 33 is arranged to travel externally of the casing and circumferentially of the valve during rotation of said stem and spaced, in the fully open position of the 5 valve, from the flange 30 circumferentially of the valve in one direction, and that the member 37 of the arm 35 is arranged to be moved under and across the hole 31 in said flange by and during rotation of said stem 10 in the direction and to the extent required to lower the valve from said open position into its closed position.

The rearward portion 38 of the flange 30 is imperforate and, when the valve is closed, 15 extends over the member 37 of the arm 35, as shown in Fig. 3. Figs. 1 and 3 illustrate the application of a padlock 40 to the flange 30 when the valve is closed and show the bow 41 of said lock as extending through 20 the hole 31 in said flange and next forward of the member 37 of the arm 35 of the handle and, therefore, said bow is arranged to cooperate with said member 37 of said arm in preventing leftward movement of the handle 25 from the position shown in Fig. 1, to the position shown in Fig. 4 until after the padlock has been removed from said flange. It will be observed that said member 37 of said arm, in the position of the handle shown in 30 Fig. 3, is not only opposite the bottom of the imperforate rearward portion 38 of the flange 30 but considerably nearer the bottom of said flange (see Fig. 1) than the lower 35 extremity of the valve-stem-embracing portion of the handle is to the extremity of the valve-stem, so that said flange and said member of the handle are arranged to cooperate, when the valve is closed, in preventing forcible removal of the handle upwardly 40 from said stem.

What I claim is:—

1. A faucet comprising a casing having an interior chamber which has a fluid-inlet and a downwardly discharging fluid-outlet, a valve arranged to control communication through said outlet and movable upwardly in opening and having a rotatable stem which extends upwardly above the casing and has an external thread, an upright spout-forming tube rigid with the casing and communicating with and arranged wholly below said outlet, the casing having a seat for the valve at and around said outlet and also having a screw-threaded aperture which extends through the top of the casing and is concentric in relation to the valve, and a stuffing-box comprising an externally threaded body which surrounds said stem and is screwed at said aperture into the casing and has a lower end face and an internal thread engaging with the thread on said stem, the mutually engaging threads of said stem and said body having the pitch required to move the valve from its closed 60 position into its fully open position sub-

stantially during a half turn of said stem about its axis, and the valve abutting, in its fully open position, against the aforesaid face.

2. A faucet comprising a casing having an 70 interior chamber which has a fluid-inlet and a downwardly discharging fluid-outlet, a valve arranged to control communication through said outlet and having a stem which extends upwardly above the casing and has 75 an external thread, an upright spout-forming tube rigid with the casing and arranged below and communicating with said outlet, the top of the casing having an aperture which extends therethrough over said outlet 80 and has an upwardly flaring upper end portion and is screw-threaded below said portion and concentric in relation to the valve, and a stuffing-box comprising a body which surrounds said stem and has an internal 85 thread engaging with the thread on said stem and also has an external downwardly facing annular beveled shoulder which is in fluid-tight relation to the surrounding wall of said portion of said aperture, said body 90 being externally threaded below said shoulder and screwed at said aperture into the casing below said portion of said aperture and having a lower end face below said aperture, and a portion of the valve overlapping 95 said face when the valve is fully open.

3. A faucet comprising a casing which has an interior liquid-receiving chamber having a downwardly discharging fluid-outlet and also has an external flange having a hole extending from top to bottom of the flange, a valve arranged to control communication through said outlet and having a rotatable stem which extends upwardly 100 above the casing and has an external thread, a stuffing-box comprising a body which surrounds the valve-stem and is rigid with the casing and has an internal thread engaging with said thread on said stem, and a handle 105 operatively embracing said stem and having an arm arranged to travel externally of the casing and circumferentially of the valve during rotation of said stem and spaced, in the fully open position of the 110 valve, from the aforesaid flange circumferentially of the valve in one direction, said arm being arranged to be moved, by and during rotation of said stem in the direction and to the extent required to actuate 115 the valve from said open position into its closed position, substantially just beyond the aforesaid hole so as to permit the extension, through said hole, of the bow of a 120 padlock when the valve is closed.

4. A faucet comprising a casing which has an interior liquid-receiving chamber having a downwardly discharging fluid-outlet and also has an external flange having a hole extending from top to bottom of the 130

flange, a valve arranged to control communication through said outlet and disposed to move upwardly in opening and having a rotatable stem which extends upwardly 5 above the casing and has an external thread, a stuffing-box comprising a body which surrounds the valve-stem and is rigid with the casing and has an internal thread engaging with said thread on said stem, and a handle 10 operatively embracing said stem and having an arm arranged to travel externally of the casing and circumferentially of the valve during rotation of said stem, said arm being spaced, in the fully open position of 15 the valve, from the aforesaid flange circumferentially of the valve and having a member arranged to be moved under and across the aforesaid hole by and during rotation of said stem in the direction and to 20 the extent required to actuate the valve from said open position into its closed position.

5. A faucet comprising a casing which has a liquid-receiving chamber having an outlet at the bottom and also has an external flange having a hole extending from 25 top to bottom of the flange, a valve controlling communication through said outlet

let and arranged to move upwardly in opening and comprising an upwardly extending rotatable stem having an external 30 thread, a stuffing-box comprising a body which surrounds the valve-stem and is rigid with the casing and has an internal thread engaging with said thread on said stem, and a handle operatively embracing the upper 35 end of said stem and comprising an arm arranged to travel externally of the casing during rotation of said stem, said arm being spaced, when the valve is fully open, from the aforesaid flange circumferentially 40 of the valve and having a member arranged to be moved under and across the aforesaid hole during the valve-closing movement of the valve-stem, and a portion of said flange, when the valve is closed, extending over 45 said member of said arm and being nearer the bottom of said flange than is the lower extremity of the valve-stem-embracing portion of the handle to the upper extremity 50 of the valve-stem.

In testimony whereof I sign the foregoing specification.

JOSEPH A. COSTELLO.
